UNITED STATES PATENT OFFICE

2,533,857

BULL BRIDLE

Marion Roger Warrick, Greenville, Ohio

Application June 28, 1949, Serial No. 101,851

7 Claims. (Cl. 119—142)

1

This invention relates to a bull bridle.

An object of the invention is to provide an efficient apparatus that is attached to the head of the bull for preventing him from butting, and especially for preventing him from destroying feed racks, pens, fences and gates.

A still further object of the invention is the provision of means for making it safer to have the bull around, as the invention eliminates the possibility of the bull goring people. The fact is that more people are killed by bulls than any other animal.

A still further object is the provision of an efficient bull bridle that does not interfere with the normal functions of a bull nor does it hinder his eyesight.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a perspective view of the apparatus, shown on a bull.

Figure 2 is a top plan view of the apparatus.

Figure 3 is a view in front elevation.

Figure 4 is a view in side elevation.

Figure 5 is a sectional view, taken on lines 5—5, Fig. 3.

Figure 6 is an enlarged, fragmentary view of the chain, showing a snap on one end thereof.

Referring to the drawings, in which the preferred embodiment of this invention is illustrated, there are three main units, to wit: the halter 1, the swinging or rocking head frame 2, and the pivotally mounted nose section 3.

The halter 1 comprises a primary halter section 4 and an auxiliary halter section 5. The primary halter section 4 has a plurality of apertures 6 on each side portion, the primary halter section 4 being in the shape of an inverted U. The auxiliary halter section 5 is also provided with apertures 7 on its sides, as this section 5 is in the shape of a U. By means of the apertures 6 and 7, the auxiliary halter section 5 can be adjusted upon the primary halter 4, by causing different apertures to register on these sections. Bolts 8 are employed to hold the auxiliary halter section 5 in an adjusted position upon the primary halter section 4. A curved forehead section 10 is fixedly secured at its inner end to the inner portion of the auxiliary halter section 5. This forehead section 10 has a plurality of apertures 11. Fig. 2, formed near its upper or outer

2

end, whereby the curved forehead section 10 can be adjustably secured to the top part of the primary halter section 4. A screw 12, Fig. 5, is employed for securing the forehead section 10 in an adjusted position. There are two chains employed in the halter construction, one being the upper chain 13 and the other the lower chain 14. Each chain is provided with a snap 15, Fig. 6. The upper chain 13 is secured at one end in one of the apertures 7 of the auxiliary halter section 5 and the other end is provided with a snap 15, Fig. 2. The lower chain 14 is fastened at one end to one of the sides of the primary halter section 4, Fig. 3, and the snap 15 at its other end is snapped into an aperture in the primary halter section 4. When the halter section 1 is placed on the bull's head, then the operator places the chains under the head and partly around the neck of the animal, and then snaps the chains in a fixed position on the halter, whereby the halter is securely mounted on the animal.

The horizontal head frame 2 normally above the animal's head comprises a loop section 16 spaced from the animal's head, which has integral therewith at its center an upstanding curved integral section 17. When the bull attempts to butt, the loop section 16 or the curved section 17 thereof is contacted and often both of these sections are at once contacted, whereupon swinging or rocking action is caused and the strain is placed on the bull ring 18, as hereinafter described.

On the loop section 16 are two depending lugs 19, Fig. 3, and on the primary halter section 4 are two upstanding lugs 20. These lugs 19 and 20 are held in engagement by bolts 21. Therefore, the head frame 2 is pivotally mounted on the primary halter section 4.

The swinging or rocking nose section 3 is of a substantial Y shape, and the prongs 22 engage at their upper ends horizontal lugs 23 that are formed integral with the swinging or rocking loop section 16. The upper ends of the prongs 22 are held in engagement by means of bolts 24, whereby the nose section 3 and the head frame 2 are pivotally connected and are adapted to move in a vertical plane. The nose section includes a snap device 25. This snap device has a shank 26 integral with a common snap 27. The shank 26 is provided with apertures 28 and by means of the cotter pin 29, the shank is adjustably mounted on the Y-shaped nose section 3. The snap 27 is fastened in the bull ring 18, Fig. 1, whereupon any impact or contact of the nose section 3 or

the head frame 2, or both, will cause the bull to desist in further butting, etc.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an apparatus of the class described, the combination of a halter comprising a primary halter section, an auxiliary halter section mounted on said primary halter section, a forehead section attached to said auxiliary halter section and to said primary halter section, a head frame normally spaced above an animal's head movably mounted on said halter section, and a nose section normally spaced above an animal's head movably mounted on said head frame.

2. In an apparatus of the class described, the combination of a halter comprising an inverted U-shaped primary halter section having spaced lower ends, said primary halter section provided with a plurality of apertures on its side, an auxiliary halter section against said primary halter section, means extending through portions of said auxiliary halter section and positioned in some of said apertures of said primary halter section, fastening said two sections together, a curved forehead section fixedly secured at its lower end to said auxiliary halter section, means adjustably connecting the upper end of said forehead section to said primary halter section, a head frame spaced from an animal's head and movably mounted on said halter, and a nose section movably mounted on said head frame.

3. In an apparatus of the class described, the combination of a halter provided with upstanding lugs, a swinging head frame provided with depending lugs registering with said upstanding lugs, fastening means extending through said lugs and pivotally connecting said halter and head frame, and a nose section movably mounted on said head frame.

4. In an apparatus of the class described, the combination of a halter, a swinging head frame and means pivotally mounting said head frame on said halter, said head frame comprising a horizontal loop section, an upstanding curved section integral with the center of said loop section, said loop section provided with horizontal lugs, and a nose section pivotally mounted on said lugs.

5. In an apparatus of the class described, the combination of a halter, a swinging head frame movably mounted in a vertical plane on said halter, said head frame provided with lugs, a Y-shaped nose section provided with prongs engaging said lugs, means connecting said prongs and lugs together, and said nose section provided with means for attaching same to a bull ring.

6. In an apparatus of the class described, the combination of a halter, a swinging head frame movably mounted in a vertical plane on said halter, a nose section movably mounted on said head frame, said nose section provided with a snap device, said snap device provided with a shank extending into said nose section, and means extending through a portion of said nose section and through said shank, holding the shank and nose section together.

7. In an apparatus of the class described, the combination of a halter, a swinging head frame movably mounted in a vertical plane on said halter, a nose section pivotally mounted on said head frame, said nose section provided on its lower end with a snap device, said snap device having an apertured shank, and fastening means extending through a portion of said nose section and through an aperture of said shank, holding the shank and nose section together.

MARION ROGER WARRICK.
